Chas Reistle.

United States Patent Office.

CHARLES REISTLE, OF BROOKLYN, NEW YORK.

Letters Patent No. 77,215, dated April 28, 1868.

IMPROVED TUMBLER-HOLDER.

The Schedule referred to in these Letters Patent and making part of the same.

TO ALL WHOM IT MAY CONCERN:

Be it known that I, CHARLES REISTLE, of Brooklyn, in the county of Kings, and State of New York, have invented, made, and applied to use, a certain new and useful Improvement in "Tumbler-Holders;" and I do hereby declare the following to be a full, clear, and exact description of said invention, reference being had to the annexed drawing, making part of this specification, which represents—

A section of my "holder" as applied to a tumbler.

In the drawing, *a* is a tumbler, *b* the handle. *c c* is a ring, soldered to the lower part of the handle. *d* is a projection, permanently attached to the handle, to which is secured, by a pin, a button, *e*.

The object of my invention is to produce a holder for soda-water tumblers, which shall have a handle, and which can be attached to a tumbler quickly and firmly, and that can be manufactured at a comparatively small cost.

In drawing soda-water, it very frequently overflows the tumbler, making it impossible to handle the tumbler without soiling the hands; but, with my improved holder, that difficulty is entirely overcome, as the handle which I provide sets off from and above the tumbler.

Holders for tumblers have been made, but they are large and occupy a great deal of room, and have a much greater surface to be cleaned than those made on my improved plan, and cost considerably more to manufacture.

I make my handle, *b*, of German silver, brass, or any other material, to which is soldered a ring, *c c*, which is made flaring, so that it will fit the sides of a tumbler. *d* is a projection, which fits on the top edge of the tumbler, to which projection is fixed a movable button, *e*, which works on the pin *f*, which, when pressed down, retains the tumbler in the holder.

To attach my holder to a tumbler, it is only necessary to place the bottom of the tumbler in ring *c c* and press the projection *d* over the top edge of the tumbler, having previously raised the button *e*, and then, by turning the button down, it will be seen that it is impossible to remove the handle without turning the button, and if a tumbler should be broken in use, it will require but a moment of time to fit the same handle to another tumbler.

The holder can be made ornamental by engraving or chasing, and, when plated and burnished, will tend to give the tumbler a handsome appearance.

My improved holder will be found very convenient to be used on tumblers in which hot drinks are served. Having thus fully described my invention, what I claim, and desire to secure by Letters Patent, is—

A tumbler-holder, having a handle, *b*, ring *c c*, projection *d*, and button *e*, in substantially the manner described and shown, and for the purposes set forth.

In witness whereof, I have hereunto set my signature, this thirteenth day of March, in the year of our Lord one thousand eight hundred and sixty-eight.

CHS. REISTLE.
